UNITED STATES PATENT OFFICE

RUDOLPH DE BOER, OF GRAND RAPIDS, MICHIGAN, ASSIGNOR TO GRAND RAPIDS METALCRAFT CORPORATION, OF GRAND RAPIDS, MICHIGAN, A CORPORATION OF MICHIGAN

DESIGN FOR AN AUTOMOBILE INSTRUMENT PANEL

Application filed March 17, 1930. Serial No. 34,913. Term of patent 3½ years.

To all whom it may concern:

Be it known that I, RUDOLPH DE BOER, a citizen of the United States, residing at No. 22 Commerce Avenue, S. W., Grand Rapids, in the county of Kent and State of Michigan, have invented a new, original, and ornamental Design for an Automobile Instrument Panel, of which the following is a specification reference being had to the accompanying drawing forming a part thereof, in which:

Figure 1 is a front elevational view of the automobile instrument panel, showing my new design; and

Figure 2 is a side elevational view thereof, enlarged.

I claim:

The ornamental design for an automobile instrument panel, substantially as shown.

RUDOLPH DE BOER.
